HIGH-FREQUENCY HEATING SYSTEM

Lloyd D. MacDermaid, St. Charles, Ill., assignor
to Operadio Manufacturing Company, St.
Charles, Ill., a corporation of Illinois

Application November 2, 1946, Serial No. 707,508

5 Claims. (Cl. 219—47)

1

This invention relates to an electrical apparatus and particularly to a machine for assembling into an integral unit a voice coil bobbin, diaphragm and spider for use in loud speakers. The above assembly, as used in dynamic speakers, is adapted to operate in an annular air gap having a relatively small transverse dimension. Thus, in most instances, the air gap dimension is of the order of several thousandths of an inch. It is essential that the voice coil and bobbin assembly be uniform, strong and as thin as possible. The invention hereinafter described provides a machine for assembling a bobbin, spider and diaphragm into a unitary assembly. The machine utilizes high frequency currents for cementing materials to be assembled.

The invention in general provides machines for making the assembly in units of two, said two machines being operated in push-pull. Any lack of symmetry in high frequency potentials will be eliminated and more uniform operation will result.

For a more complete description of the invention, reference will now be made to the drawings wherein Figure 1 is a top plan view of two assembly units. Figure 2 is a sectional elevation on line 2—2 of Figure 1 showing one of the units. Figure 3 is an end elevation of the two units. Figure 4 is a detail of one of the insulating rings used in a unit. Figure 5 is a section on line 5—5 of Figure 4. Figure 6 is a circuit diagram of one system. Figure 7 is a circuit diagram of a modified system.

Inasmuch as all the units are similar in construction, a detailed description of only one will be given. Thus, base 10 is provided with tubular standard 11 having reduced end 12 adjustably disposed in a suitable aperture in base 10. Set screw 14 is provided to lock standard 11 in position. Standard 11 has threaded portion 16 and terminates in machined annular conical tip 17. Conical tip 17 has flat annular end 18. Standard 11 is provided with cylindrical tubular channel 20, the upper portion of which is enlarged to form channel 21. Channel 21 extends to the top of the standard.

Disposed around threaded portion 16 of the standard is flanged ring 23 engaging threaded portion 16 and locked in position by lock nut 24. Flanged ring 23 has threaded portion 26 50

and machined supporting surface 27. Rotatably supported on bearing surface 27 is flange ring 30 whose bottom surface 31 rests on annular supporting surface 21. Retainer ring 32 has threaded portion 33 cooperating with threaded portion 26 of flange 23. Retainer ring 32 has collar portion 34 adapted to cooperate with split ring 35 disposed in slot 36 in the lower portion of flange ring 30.

10 Flange ring 30 is made of any suitable metal and is preferably formed of bronze. However, the flange ring may be formed of brass, steel or any other desired material.

Flange ring 30 has a series of apertures 38 and another series of apertures 39, an aperture of one series alternating with an aperture of the other series. The peripheral portion of flange ring 30 is machined at 40 to provide an annular region upon which is bolted insulating ring 42. 15 Insulating ring 42 is preferably of glass, quartz or other material having low dielectric losses at radio frequencies. As is clearly evident in Figures 4 and 5, insulating ring 42 has a series of apertures 44 and another series of apertures 45, the two being so arranged that one alternates with the other. Apertures 45 have enlarged counter-sunk portions 47 extending up from bottom face 48 of ring 42. Apertures 44 have reduced portions 49 at the lower face of the ring, apertures 44 and 49 being similar to apertures 45 and 47 except that they are reversed.

As will be evident from Figure 2, apertures 38 in flange ring 30 are the same size as aperture 49 in ring 42, while apertures 39 in flange ring 30 are the same size as aperture 47 in the ring. Apertures 38 of flange ring 30 and apertures 39 of flange ring 30 respectively register with the apertures 49 and 47 in the insulating ring.

Flange ring 30 has end portion 50 so shaped 40 as to form a continuation of annular conical surface 17 of standard 11. End portion 50 terminates in annular portion 51 adjacent insulating ring 42.

Supported on insulating ring 42 is top ring 53 45 of any suitable metal such as bronze, brass or the like. Top ring 53 has machined annular surface 54 resting against the top face of insulating ring 42. Top ring 53 is provided with threaded blind recesses 55 registering with apertures 45 in the insulating ring.

As will be evident from Figure 2, insulating ring 42 is rigidly bolted to flange ring 38 by bolts 56, while top ring 53 is bolted to the insulating ring by bolts 57.

Top ring 53 has a plurality of annular step portions 59, 60 and 61. Each of these step portions forms an annular ring, and the lowest and innermost step portion 61 is shaped to provide an upwardly and inwardly extending annular finger 63. The bottom of top ring 53 has annular surface 64 and tapering surface 65 defining the bottom portion of annular finger 63. It will be noted that the inside diameter of annular finger 63 is somewhat greater than the diameter of cylindrical channel 21 for a reason to be apparent later. Top ring 53 has peripheral flange 67 with a machined top supporting surface 68 upon which is adapted to be disposed an annular insulating retaining member 70 of wood or the like. Retaining member 70 has overhanging flange portion 71 telescoping flange 67.

Telescoped within cylindrical portion 21 is metallic sleeve member 73. Sleeve 73 has its bottom 74 somewhat short of the top end of inner wall 20 of standard 11. Sleeve 73 has its top end 75 substantially in line with the tip of annular finger 63. Sleeve 73 fits sufficiently tight within enlarged bore 21 to remain in position but may be removed and replaced by another sleeve of different thickness. Sleeve 73 has a predetermined wall thickness to provide an annular region 77 between the inside of sleeve 73 and center post 79 disposed within standard 11 and having reduced portion 80 actually defining the annular region 77. As will be apparent from Figure 2, reduced portion 80 of the central post extends upwardly for a substantial distance above annular finger 63.

Supported from top end 81 of post 79 is a die assembly comprising annular die block 83 having cylindrical recess 84 formed therein. Fitting smoothly into recess 84 is tapered die member 85, this comprising a generally cylindrical block having cylindrical recess 86 formed therein, this cylindrical recess having a sufficiently large diameter to provide an annular clearance around reduced portion 80 of the central post. The tapered top is adapted to expand the neck of the diaphragm cone so that it will go on the outside of the voice coil bobbin as seen in Figure 8. Die member 83 and tapered die member 85 have the bottom ends shaped to provide annular faces 87 and 88 respectively. Annular face 88 is adapted to be disposed opposite top end 75 of sleeve 73 but spaced at a slight distance therefrom to provide gap 90.

Die member 83 has threaded top 91 into which is disposed stop bolt 92 adjusted to any desired position by lock nut 93. Stop bolt 92 is adapted to rest against top face 81 of the top end of post 79 and thus determine a limit to the position at which the entire assembly may drop. Cap 95 may be threaded over die portion 83 to enclose stop bolt 92 and protect the same. Post 79 is vertically slidable in standard 11 and may be actuated by handle 97 disposed in the bottom of post 79 just above base 10. Standard 11 is provided with clearance slot 98 in which handle 97 may move during vertical travel of post 79. It is apparent that, when handle 97 is raised upwardly, post 79 will be moved upwardly to raise the entire die assembly resting on the top end of the post.

The vibratory assembly portion of a speaker shown in Figure 8 comprises voice coil bobbin

100 carrying voice coil 101 thereon. Bobbin 100 has its top end 102 rigidly fastened to inner edge 103 of spider 104. Spider 104 may take on a variety of forms as well known in the art and may consist of a true spider having a plurality of legs or may consist of an annular disc. Spider 104 is provided with annular mounting region 105. Upper portion 102 of bobbin 100 fits into and is rigidly attached to neck 107 of conical diaphragm 108 having corrugated peripheral portion 109 and annular mounting portion 110.

Bobbin 100, spider 104 and diaphragm 108 may be formed of any suitable material, such as paper, fiber or the like, and have their overlapping parts 102, 103 and 107 cemented together. The cement used may be either thermo-setting or thermoplastic or a combination of both. Thus, if a speaker is to be used under normal temperature conditions, then thermoplastic cement alone may be used. On the other hand, if the speaker is to be used under conditions where elevated temperatures are encountered, then a thermo-setting cement is necessary.

Where a thermo-setting cement is necessary, it is desirable to provide a mixture of both thermoplastic and thermo-setting cements. In that way, initial cementing due to the thermo-plastic cement is secured.

Cements, in general, have substantial dielectric losses at radio frequencies and, thus, are useful in dielectric heating. A thermoplastic cement available in the trade under the trade-name Vinylseal may be used, while a combination of thermo-setting and thermoplastic cement is made by Bakelite Corporation and sold as No. 16320. Both of these cements are useful for the speaker parts, since the dielectric losses are concentrated therein rather than paper, fiber, cured Bakelite or other material of which the bobbin, spider and diaphragm are generally formed.

Bobbin 100 and voice coil 101 are disposed around sleeve 73 in the free annular region between parts 17 and 64. Spider 104 is disposed in position so that mounting portion 105 rests on step 60 while the inner edge portion rests in gap 90. Similarly, diaphragm 108 has its inner edge disposed in gap 90 while the outer mounting portion 110 is clamped between insulating member 70 and flange 67.

As will be evident from the electrical connections, high frequency potentials are applied between sleeve 73 and annular finger 63 across the annular air gap. Some potential is also applied between bottom faces 87 and 88 of the die blocks and annular finger 63. The annular region to be cemented is disposed between annular finger 63 and the sleeve, this region being accommodated by enlarged annular region 66.

As previously indicated, the units are operated in tandem.

To this end, top ring 53 has boss 115 formed thereon, said boss extending from one side of the unit. Boss 115 is provided with vertically disposed aperture 116 and a sidewardly disposed threaded aperture 117. Two units are disposed as shown in Figure 1 with bosses 115 and 115' extending toward each other. A U-shaped metallic connecting member 120 has arms 121 and 122 extending down through apertures 116 and 116' of the opposing bosses. Connecting member 120 may be locked in any desired vertical position by thumb screws 123 and 123' disposed in threaded apertures 117 and 117' respectively.

Connecting member 120 is so dimensioned and shaped as to constitute inductance at the fre-

quencies used in the system. Thus effective tuning of a pair of units may be accomplished by vertical adjustment of U-shaped connecting member 120. This connecting member is preferably formed of material such as copper having a high degree of conductivity and has sufficient surface area so that the ohmic resistance is reduced to a satisfactory low level. It is understood that member 120 need not necessarily be solid and may be a bent tube.

As has been pointed out previously, the dielectric heating units are operated in pairs. Referring now to Figure 6, a diagrammatic showing of a system is disclosed. Here, oscillator 130 is connected through lines 131 and 132 to units 133 and 134. Units 133 and 134 are connected by looped member 120. As shown in Figure 1, oscillator 130 may be disposed in any suitable casing and may have knob 136 for controlling the frequency. Handles 137 and 138 may control suitable contact members 139 and 140 for making contact with leads to the units. As shown in Figure 3, a pair of heating units are disposed on a circular table, only part of which is shown. This table is adapted to be moved intermittently past oscillator 130 so that successive pairs of heating units may be operated. Clamping members 137 and 138 are merely for the purpose of providing a convenient detachable connection.

Referring now to Figure 7, a modified diagrammatic system is shown. In this system, oscillator 142 has output loop 143. Output loop 143 is inductively connected to loop 145 which is electrically one wave length long around the complete loop. Loop 145 has end 146 provided with meter 147 connected between two spaced points at the loop end. Dielectric heating units 150 and 151 are connected substantially at the electrical midpoints of loop 145. Loop 145 has end 152. Tuning condenser 153 is connected across the loop between end 152 and dielectric heating units 150 and 151. Condensers 154 and 155 are connected in series across the loop between end 146 and the dielectric heating units. The various condensers are provided for the purpose of insuring balance and symmetry. The condensers may be variable if desired to compensate for changing conditions.

In order to prevent destruction of any unit in case an arc occurs, it is possible to incorporate within the dielectric heating system a protective circuit described and claimed in the pending application of John McW. Stone, S. N. 578,677 filed February 19, 1945, now Patent 2,454,618 issued November 23, 1948. As applied to Figure 7, lead 158 may be connected to end 152 of the loop, while lead 159 may be connected through a radio frequency choke 160 to end 146 of the loop. A suitable high potential, either direct or alternating at a comparatively low frequency such as 60 cycles per second, may be applied to the two leads. It is evident that, if an arc occurs in either of units 150 or 151, a low impedance connection is established and current will flow. In lead 159, for example, there may be connected relay 156 controlling the power input to oscillator 142.

The same protective system may be applied to the circuit shown in Figure 6.

What is claimed is:

1. For use in cementing an assembly of bobbin, spider and diaphragm all of insulating materials and used in a speaker, the inner edge por-

tion of said spider and diaphragm being disposed at the end portion of the bobbin with cement at the meeting surfaces to provide an annular cementing region in which heat is to be generated, a dielectric type of heating system comprising a first metal die member having an annular recess for accommodating the bobbin, a second metallic annular die member insulatingly supported with respect to said first die member, said second die member having the inner edge formed as an annular finger, means for supporting the diaphragm and spider against the bobbin end in position for cementing with the first two die members disposed on the same side of both diaphragm and spider and with the annular finger of said second die member extending to the cementing region, a third metallic die member having an annular portion, means for supporting said third die member on the other side of said spider and diaphragm with the annular portion disposed opposite to the annular finger but separated therefrom by the spider and diaphragm material, means for insulating said second and third die members from each other and means for applying high frequency potentials to said second and third die members to generate high frequency electric fields between the opposed annular die portions at the cementing region.

30 2. The structure of claim 1 wherein said first die member has a portion extending within the bobbin beyond the diaphragm and spider and wherein said third die member is supported from said last named portion, said second and third die members cooperating to maintain the parts at the cementing region in position during heating.

35 3. For use in cementing an assembly of bobbin, spider and diaphragm, all of insulating materials and used in a speaker, the contacting surfaces having cement and forming a cementing region in which heat is to be generated, a dielectric type of heater comprising the following: a metal sleeve and rod longitudinally movable in said sleeve, said rod and sleeve being shaped to provide an annular recess at one end of the sleeve for accommodating a bobbin, said rod extending beyond the sleeve end, an annular die member having its inner edge shaped to provide an annular finger, means for insulatingly supporting said die member rigidly with respect to said sleeve so that the annular finger is beyond the open sleeve end and around but spaced from said rod, means for supporting the diaphragm and spider on said die member so that the inner edges thereof contact the bobbin end for cementing, an additional die member supported from said rod and having an annular portion fitting against the inner edge portion of said diaphragm and spider to press the same against the bobbin, and means for applying high frequency potentials to said annular die member and additional die member to generate heat at said cementing regions, said rod and post being movable to release said cemented assembly clear after removal of said other die.

40 4. The structure according to claim 3 wherein a loose ring is provided for retaining the outer edge of the diaphragm against said annular die member, said post and sleeve normally being vertical with said ring member resting on the outer edge of said diaphragm by gravity.

45 5. A pair of structures according to claim 3 and a U-shaped connector between said struc-

70 75

tures with said structures being connected in series to the source of high frequency potential.
